UNITED STATES PATENT OFFICE.

ISIDORE MARKS, OF BOSTON, MASSACHUSETTS.

HORN-REED.

1,390,305.

Specification of Letters Patent. Patented Sept. 13, 1921.

Application filed October 5, 1920. Serial No. 414,747.

To all whom it may concern:

Be it known that I, ISIDORE MARKS, a citizen of the United States, residing at Dorchester, Boston, in the county of Suffolk and 5 State of Massachusetts, have invented certain new and useful Improvements in Horn-Reeds, and I do hereby declare the following to be a full, clear, and exact description of the invention, such as will enable others 10 skilled in the art to which it appertains to make and use the same.

The present invention relates to horn reeds and more particularly to reeds for use in toy horns.

15 One of the objects of the invention is to provide an improved horn reed having separate component parts which may be manufactured at a minimum cost and quickly and easily assembled.

20 To the accomplishment of this object and such others as may hereinafter appear, as will be readily understood by those skilled in the art, the invention consists in the improved construction and arrangement of 25 parts illustrated in the accompanying drawings, and particularly pointed out in the appended claims.

In the drawings, illustrating what is now 30 considered the preferred embodiment of the invention, Figure 1 is a longitudinal sectional view of a toy horn provided with the improved reed; and Figs. 2, 3 and 4 are detail perspective views of the several component parts of the reed before being 35 assembled.

Referring to Fig. 1 of the drawings, the improved horn reed comprises a tongue or 40 vibrator 5, a coöperating throat piece 6, and a reed block or holder 7, in which the tongue and throat piece are mounted. The reed block 7 is fitted within the small end of the 45 horn 8 and may be secured thereto by any suitable means.

The tongue 5 consists of a piece of thin 45 brass or other suitable material of slightly tapering form. The smaller end of the tongue has a rounded margin, while the larger end of the tongue is shaped as shown in Fig. 2, having slight marginal extensions 50 9 at opposite sides thereof.

The throat piece 6 is trough-shaped having a substantially semi-circular cross-sectional contour. As shown in Fig. 3, one end of the throat piece is open while the opposite end thereof is closed by a convex end

wall 10. The sides of the throat piece converge slightly toward the closed end to conform to the taper of the tongue. An outwardly turned flange 11 extends along the margin of the throat piece, at the opposite 60 sides and closed end thereof. This marginal flange 11 is shaped as clearly illustrated in Fig. 3, all portions of the flange lying in the same plane.

The real block or holder 7, as shown in 65 Fig. 4, consists of a disk of substantial thickness having a central opening 12 adapted to receive the throat piece and the tongue. To this end the opening 12 is substantially semi-circular in outline, and has approximately 70 the same radius of curvature as the sides of the throat piece. The disk 7 is further provided with narrow cuts or notches 13 extending laterally from the opening 12 at oppositely disposed points in the wall thereof. 75 These notches 13 are adapted to receive the opposite ends of the flange 11 of the throat piece and the lateral extensions 9 of the tongue. In order that said parts may be tightly gripped and firmly pressed together 80 when forced into said notches, the latter are made sufficiently narrow to insure that they will be enlarged slightly by the insertion 85 therein of the tongue and throat piece flange. The side walls of the notches 13 on the opposite side of the disk from the semi-circular wall of the opening 12 are connected by a slightly concave wall 14. With this construction the outer face of the tongue and the adjacent wall of the opening 12 will be 90 separated, between the tongue extensions 9, by an open space, the advantage of which 95 will be hereinafter explained.

In assembling the parts of the reed, the tongue 5 and the throat piece 6 are first held 100 together manually in the relative positions in which they appear in Fig. 1. The rounded ends of these parts are then slipped into the opening 12 in the disk 7 and forced through said opening until the opposite 105 ends thereof are substantially flush with one face of the disk. The tongue, the throat piece, and the disk opening 12 are so proportioned that when the tongue and throat piece are assembled and forced into said 110 opening they will fit tightly therein so as to be frictionally held in contact with each other and with the disk. The tongue will then be securely held in position opposite the open side of the throat piece so that it is

adapted to produce sound when vibrated by blowing the horn. Advantageously the disk 7 may be made of relatively yielding or compressible material such, for example, as fiber 5 or heavy pasteboard. By constructing the disk of such material, the side walls of the notches 13 may be more readily spread apart as the interposed parts of the reed are wedged between them. This will insure that 10 said parts will be securely held in assembled position. After the disk 7 is secured in place in the interior of the horn, the projecting portions of the tongue and throat piece will be confined in a chamber formed between 15 the disk and the mouth piece 15 of the horn, so that they will be protected from liability of accidental displacement.

In reeds of the above-described general character, as heretofore constructed, the 20 tongue is liable to buckle or arch transversely toward the interior of the throat piece. A tongue thus buckled will not vibrate properly and consequently the horn will not sound properly when blown. In the 25 present construction, by reason of the open space provided between the outer face of the tongue and the adjacent wall 14 of the disk opening 12, there is no tendency for the tongue to buckle in the objectionable manner above set forth and thus interference 30 with the proper vibration of the tongue will be avoided.

It will be seen that a reed constructed in accordance with the present invention may 35 be very cheaply manufactured, and the parts thereof quickly and easily assembled. When assembled, they are securely held together without the use of solder or other fastening means.

40 While it is preferred to employ the specific construction and arrangement of parts shown and described, it will be understood that this construction and arrangement is not essential except so far as specified in 45 the claims, and may be changed or modified without departing from the spirit and true scope of the invention.

What is claimed as new, is,—

1. A horn reed comprising a tongue having 50 marginal extensions adjacent one end, a trough-shaped throat piece having a marginal outwardly extending flange, and a disk composed of compressible material having a substantially semi-circular opening with cuts 55 extending in opposite directions therefrom, the opening between the walls of said cuts

being less than the combined thickness of the marginal portions of the tongue and throat piece, the throat piece and tongue being mounted in the disk opening with the tongue 60 at the open side of the throat piece and the flange of the throat piece and the marginal extensions of the tongue held in contact with each other in said cuts by frictional contact with the disk caused by compression of its 65 material.

2. A horn reed comprising a metallic trough-shaped throat piece having a marginal outwardly extending flange, a metallic tongue associated therewith of a width to 70 engage said flange, and a reed block comprising a fiber disk adapted to be secured within the horn tube and having a central opening of substantially the cross-section of the throat piece, and opposite cuts extending 75 in alinement from the walls of said opening of a length adapted to receive the overlying margins of said tongue and throat piece, but of less width than the combined thickness of said margins, whereby when the 80 reed is assembled the walls of the cuts in the fiber disk are wedged apart by the thicker margins of the metallic tongue and throat piece.

3. A horn reed comprising a tongue, a 85 trough-shaped throat piece having a marginal outwardly extending flange, and a disk having an opening with a substantially semi-circular wall and oppositely disposed notches extending outwardly in opposite directions from said opening, the tongue and the throat piece being mounted in the opening in the disk with the tongue closing the open side of the throat piece and the flange 90 of the throat piece and marginal portions of the tongue held in contact with each other by insertion within said notches, said opening having a wall opposed to said substantially semi-circular wall which is shaped to 95 provide an open space between the outer face of the tongue and the disk when the parts are assembled.

4. A reed block for sound producing toys comprising a disk having an opening defined by a substantially semi-circular wall, the 105 walls of a pair of notches extending outwardly in opposite directions from said opening at the opposite ends of said wall, and a concave wall connecting the walls of said notches which are opposite those connected by said semi-circular wall.

ISIDORE MARKS.
